UNITED STATES PATENT OFFICE.

EDWARD S. PIPER, OF TORONTO, ONTARIO, CANADA.

SIGNAL-LAMP.

SPECIFICATION forming part of Letters Patent No. 249,794, dated November 22, 1881.

Application filed August 20, 1881. (No model.)

To all whom it may concern:

Be it known that I, EDWARD SPENCER PIPER, of the city of Toronto, in the county of York, in the Province of Ontario, Canada, have 5 invented certain new and useful Improvements in Signal-Lamps, of which the following is a specification.

The object of the invention is to provide ready and effective means for securing the 10 lamp, glass, and reflector in position, so that the construction is perfectly air-tight, while the glass and reflector can be readily removed for cleaning and other purposes; and it consists, essentially, of a sheet-metal ring rolled to form 15 a screw fitting a corresponding screw upon the lamp where the glass is to be inserted, and having an internally-projecting flange formed for the purpose of butting against the face of the glass and holding it and the flanged reflector in position when the ring is screwed 20 onto the lamp, substantially as hereinafter explained.

Figure 1 are front, side, and cross-section views of the ring, glass, and reflector. Fig. 2 25 are detail views of the ring. Fig. 3 are similar views of the glass; and Fig. 4, like views of the reflector.

My invention has been specially designed 30 with the view of improving the construction of a lamp already invented by me, and for which Letters Patent No. 244,142 were granted to me July 12, 1881. In this lamp I use a reflector made in the form of a frustum of a cone, and which it is desirable should be easily got at 35 for the purpose of cleaning the chamber.

In the drawings, A is the glass, which, in the lamp illustrated, is a lens. This glass fits

within the screwed ring B, which has an internally-projecting flange, d, formed to receive the glass, as shown.

C is a reflector, having an outwardly-projecting flange, a, which also fits within the ring B, against the back of the glass. Gaskets, of rubber or other soft material, should be placed between the reflector and the end D of the lamp, 45 against which they are screwed.

It will be noticed that the ring a is screwed to fit the end D of the lamp, and that when screwed in position, with the glass and reflector located as mentioned, the end is hermetically 50 sealed, and no wind can find its way through the joints to affect the burning of the lamp within.

While my invention is specially designed for application to tail semaphore lamps, switch-lamps, buffer-lamps, mast-head lamps, and, in fact, signal-lamps generally, it is also applicable to hand lamps and lamps used for other purposes.

In order to prevent the ring B unscrewing, 60 a latch may be placed on the case of the lamp and arranged to engage with a notch or notches arranged around the circumference of the ring.

What I claim as my invention is—

A reflector made in the form of a conic frustum and flanged at its base, and a lens or face-glass, in combination with a screw-threaded collar on the body of the lamp, and a flanged and screw-threaded ring to fit over the collar and clasp the reflector and glass between it 70 and the said collar, substantially as described.

Witnesses: EDW. S. PIPER.
